UNITED STATES PATENT OFFICE.

WILLIAM W. STEWART, OF LEAVENWORTH, KANSAS.

DISPENSING-MACHINE.

1,347,416.

Specification of Letters Patent.

Patented July 20, 1920.

Application filed October 14, 1919. Serial No. 330,648.

To all whom it may concern:

Be it known that I, WILLIAM W. STEWART, a citizen of the United States, residing at Leavenworth, in the county of Leavenworth and State of Kansas, have invented new and useful Improvements in Dispensing-Machines, of which the following is a specification.

This invention relates to improvements in coin-controlled dispensing devices for dispensing liquids such as cologne and the like.

One of the objects of the invention is to provide a pumping device operated by a vertically movable part with means for holding said part stationary until the coin is introduced.

Another object of the invention is to provide means for causing the coin to release the locking means so that the pump mechanism may be actuated to force the liquid from its container.

The invention also consists in certain other features of construction and in the combination and arrangement of the several parts, to be hereinafter fully described, illustrated in the accompanying drawings and specifically pointed out in the appended claims.

30 In describing my invention in detail reference will be had to the accompanying drawings wherein like characters denote like or corresponding parts throughout the several views, and in which:—

35 Figure 1 is a front view of the invention;

Fig. 2 is a section on line 2—2 of Fig. 1;

Fig. 3 is an enlarged view partly in section, showing the operation of the dogs for controlling the plunger;

40 Fig. 4 is a view of the plunger;

Fig. 5 is a view of the coin dispensing member;

Figs. 6 and 7 are detailed views of the dogs;

45 Fig. 8 is a detailed view partly in section of the pump device.

Fig. 9 is a view of the other dog.

In these views 1 indicates a case which is composed of wood and glass, as shown, and is provided with a drawer 2 at its lower part for receiving the coins. The case contains the containers 3 for the liquid to be vended and these containers are each provided with the pump mechanism 4. Such mechanism 55 consists of the barrel 5 having its upper end engaging the stopper 6 for the container.

The lower end of the barrel is provided with an enlarged chamber 7, the inlet end of which is closed by the ball valve 8. A piston 9 is located in the barrel and the rod 10 thereof passes through a suitable packing gland 11 on the stopper. The outlet pipe 12 has its lower end connected with the chamber 7 and its upper end passing through the stopper and bent at right angles with its 65 end passing through an opening in the glass front of the case. This pipe 12 is provided with a valve 13 for preventing backward flow of the liquid. It will thus be seen that when the piston is raised the liquid in the 70 container will be sucked into the chamber and barrel and when the piston is lowered the valve 8 will prevent the liquid from returning to the container so that the liquid must pass into the outlet pipe 12 and thus 75 be forced through the open end of the same. This end may be provided with a nozzle so that the liquid will be delivered in spray form or it will be so formed as to deliver the liquid in the fine stream. 80

The upper end of the piston rod 10 is connected with a plunger 14 which is vertically movable in a guide 15 connected with the upper portion of the coin chute 16. This coin chute passes through the top of the case 85 as does also the guide and the upper end of the plunger is bent at right angles to provide a finger-engaging part 17. Outside of the case the coin chute is provided with a coin-receiving mouth 18 and said chute, within 90 the case is provided with an inclined portion 19 to carry the coin to one side of the container and then the chute passes downwardly to deliver the coin into the drawer 2. 85

In order to cause the plunger to operate 95 the pump, said plunger must first be raised to draw the liquid into the pump barrel and then lowered to force the liquid out of the pump. I provide means for locking the plunger in its lowest position and such 100 means consist of a spring-controlled dog 20 having its right angular extending tooth 21 engaging the rack teeth 22 formed on one edge of the plunger. These teeth are so formed that the dog will engage them and 105 prevent the plunger from being raised but the dog will slip over the teeth when the plunger is being lowered. I form another rack 23 on the opposite edge of the plunger, but these teeth are oppositely arranged to 110 the teeth of the other rack and such teeth are adapted to be engaged by a dog 24 piv-

totally connected to a part of the chute. This dog is held in contact with the teeth by a spring 25. This dog is normally held out of engagement with the teeth of the rack by means of a dog 26, pivotally mounted on a part of the chute and the spring 27 of which is stronger than the spring 25. This dog 26 is provided with a laterally projecting tooth 28 which engages the lower end of the dog 24 so as to hold said dog away from the teeth, owing to the fact that the spring 27 is stronger than the spring 25. The plunger 29 also carries a spring-controlled dog 29 which is adapted to engage the coin on the downward movement of the plunger. The top of the coin chute is open and receives a pusher member 30, the top of which is covered by a plate 31 provided with an extension to form a hand hold. This member 30 is provided with a laterally extending lug 32 which opens into the mouth 18 of the chute and this member is also provided with a spring 34 for engaging the coin.

It will be seen that when a coin is deposited into the mouth 8 and the member 30 is raised, said coin will pass through the opening 33 and drop onto the dogs 20 and 26. The lug 32 acts as a stop for the member 30. The said member 30 is then pushed downwardly to force the coin on the dogs, thus forcing the dog 20 out of engagement with the rack teeth and releasing the dog 24 from the dog 26. This will permit the plunger to be raised so as to cause the pump piston to suck a portion of the liquid into the barrel. The dog 24 being released from the dog 26 will engage the rack teeth 23 and thus prevent the plunger from being moved downwardly. When the plunger reaches its upper position the dog 24 will come in contact with a smooth portion of the plunger so as to permit the said plunger to be moved downwardly a slight distance in order to permit the dog 29 to engage with the coin and push the same over the dogs to release the same, thus permitting the dog 26 to move the dog 24 into inoperative position so that the plunger may be forced to its lowest position, the dog 20 riding over the rack teeth 23. Thus the liquid will be discharged from the pump mechanism and when the plunger has reached its lowest position the dog 20 will prevent it from being raised again.

I provide a stopper 35 on the end of the plunger for preventing its upward movement, and I also provide a locking strap 36 which has one end secured to the inclined

part of the chute and its other end extending over the stopper and container mouth to prevent the stopper and container being moved from the receptacle.

The drawing shows the case provided with a pair of containers, but it will, of course, be understood that one or more containers may be placed in the case.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A device of the class described comprising a case, a container therein, means for delivering the contents of the container to the outside of the case, a plunger member for actuating said delivering means, said plunger having two sets of rack teeth thereon, the teeth of which are oppositely arranged, a pair of dogs engaging said teeth, a third dog for holding one of the dogs normally out of engagement with the teeth, means for guiding a coin onto said dogs to disengage one dog of the pair from the rack and the third dog from the other dog to permit the plunger to be raised while preventing it from being lowered and means carried by the plunger for forcing the coin away from the dogs to permit the third dog to again engage the second dog to permit the plunger to be lowered.

2. A device of the class described comprising delivery means, a vertically-movable plunger for actuating said means, a dog for preventing upward movement of the plunger, a second dog for preventing downward movement of the plunger, a third dog normally holding the second dog out of operative position, a coin chute for delivering a coin onto the first and third dogs, a pusher member for causing said coin to release the first dog to permit the plunger to be raised and a dog carried by the plunger for engaging the coin to force it away from the third dog to permit it to engage the second dog to move said second dog out of contact with the plunger to permit the plunger to be lowered.

In testimony whereof I affix my signature.

WILLIAM W. STEWART.
